(57) **ABSTRACT**

A new and distinct *Cannabis* plant named 'Pure Red 3' is characterized by its unique pungent strawberry aroma that is distinct and clearly recognizable. 'Pure Red 3' has a high flower to biomass ratio and a relatively short flowering time compared with other commercial varieties known to the inventors.

11 Drawing Sheets

Specification includes a Sequence Listing.

1

Latin name of the genus claimed: *Cannabis* Hybrid.
Variety denomination: 'PURE RED 3'.

REFERENCE TO ELECTRONIC SEQUENCE LISTING

The present application contains an Electronic Sequence Listing, which is provided as a file entitled PCR008PSEQLIST.xml, which is 130,228 bytes in size, and which was created on Apr. 4, 2023, which is replaced by a Replacement Electronic Sequence Listing submitted as a file entitled PCR008PREPLACEMENTSEQLIST.xml, which is 130,059 bytes in size and was created on Jul. 19, 2023. The information in the Electronic Sequence Listing is incorporated herein by reference in its entirety.

BACKGROUND AND SUMMARY OF THE INVENTION

A novel *Cannabis* hybrid cultivar, named 'Pure Red 3' is provided. 'Pure Red 3' is the result of a planned breeding program and originated from crosses between the pollen donor (male) 'Amnesia Haze' (unpatented) and the pollen acceptor (female) 'Strawberry Haze' (unpatented). The new cultivar has been vegetatively reproduced by cloning using stem cuttings at Zeiningen, Switzerland. Vegetative clones of 'Pure Red 3' were tested in controlled greenhouses, and outdoors in open fields. The desired characteristics of each source cultivar are transferred by vegetative, asexual reproduction. 'Pure Red 3' is stable and consistently true-to-type through multiple generations of vegetative reproduction.

Cannabis is a genus of flowering plants comprising three historically distinct subspecies based on phenotype and metabolite profiles—*Cannabis sativa*, *Cannabis indica*, and *Cannabis ruderalis*. However, decades of crossing and selection makes it impossible to absolutely characterize the

2

resulting hybrid plants using phenotypic data. Most of the *Cannabis* varieties being sold for medicinal and recreational purposes contains characteristics of both *Cannabis sativa* and *Cannabis indica* subspecies. For this reason, 'Pure Red 3', described herein, has been characterized both on the presented phenotype, as well as the genotype using a series of single nucleotide polymorphisms (SNPs).

Used herein, the terms "cultivar", "variety", "clone" and "strain" are used interchangeably.

10 *Cannabis* plants synthesize unique terpeno-phenolic compounds in varying concentrations. High genetic variability has resulted in the vast varieties of chemotypes with distinct characteristics available today. More than 500 unique compounds including cannabinoids, terpenoids, terpenes, flavonoids, amino acids, vitamins among many others, are secreted as a sticky resin by the glandular trichomes found on the floral calyxes of female plants. Cannabinoids and terpenes are the biologically active chemicals responsible for the pharmacological and psychoactive properties of 15 *Cannabis* when consumed by humans. They often work together synergistically in what is commonly known as the "entourage effect" and as such, small differences in composition or concentration any of these compounds can have notable effects on the physiological effect of consumed or 20 applied *Cannabis* in or on the human body.

25 Cannabinoids are produced at significant concentrations in *Cannabis*. Although over a hundred cannabinoids have been identified in *Cannabis*, the major cannabinoids include, $\Delta 9$ -tetrahydrocannabinol (THC), cannabidiol (CBD), cannabigerol (CBG), cannabinol (CBN), cannabichromene (CBC), cannabinodiol (CBDL), cannabicyclol (CBL), cannabivarin (CBDV), cannabigerovarin (CBGV), cannabichromevarin (CBCV), tetrahydrocannabivarin (THCV), cannabidivarin (CBDV), cannabigerol monomethyl ether (CBGM), cannabilsin (CBE), cannabicitran (CBT), cannabinol propyl variant (CBNV), cannabitriol

(CBO), tetrahydrocannabinolic acid (THCA), tetrahydrocannabivarinic acid (THCVA), cannabidiolic acid (CBDA), cannabigerolic acid (CBGA) and cannabinerolic acid. These cannabinoids are usually produced by the plant in their acid form (see suffix-A), but upon heating they become decarboxylated.

Terpenes are organic molecules produced by various plants and animals. These organic compounds are responsible for the strong and distinctive smell and taste of *Cannabis*. Some of the most prominent terpenes found in *Cannabis* are myrcene, caryophyllene, and limonene, to mention a few.

The objective of the breeding program that produced 'Pure Red 3' was to develop *Cannabis* plant varieties with a unique aroma as well as unique combinations of cannabinoids and/or terpenes, while displaying a phenotype with multiple large inflorescences arranged in a naturally branched habit. The variety described herein is a result of this breeding program.

The 'Pure Red 3' cultivar was the result of a cross between 'Amnesia Haze' and 'Strawberry Haze' *Cannabis* plants. Selected progenies were then cloned and crossed by selfing using methods known in the art. In subsequent generations, the resultant plants were screened for unique and strong fruit aromas and selected based on production-relevant phenotypes. The progeny with the most stable desirable aroma, production quality, and chemotype was assigned the name, 'Pure Red 3'.

The 'Pure Red 3' plants described herein were grown both in nurseries, climate-controlled growth facilities in Zeiningen, CH, 4314 (47°32'53.5"N 7°51'53.2"E), and in the field in Niederwil, CH (47°22'49.9"N 8°18'12.6"E) during the 2022 season. Samples for metabolite analysis were taken from the flowers of numerous plants. Analytical measurements were made using Ultra Performance Liquid Chromatography by those skilled in the art. Plant phenotyping was performed using photography and subsequent analysis.

The 'Pure Red 3' variety described herein has a pungent strawberry aroma that is clearly recognizable. The aroma provides a pleasant sensory experience that is appealing to the consumer and therefore adds value to the flower as a commercial product. It furthermore has a high flower to biomass ratio and a relatively short flowering time compared with other commercial varieties.

Freeze-dried flowers from 'Pure Red 3' plants were analyzed at harvest from both greenhouse and outdoor growth environments. The terpene profiles were acquired using ethanolic extraction and HPLC methods well known to those skilled in the art. The resultant terpene content was 1.049 (% w/w) with beta-myrcene, beta-caryophyllene and bisabolol being the dominant terpenes (Table 1). The unique terpene profile has been shown not to be correlated with the unique smell of 'Pure Red 3'.

'Pure Red 3' has a cannabinoid profile in the dried mature female flowers that is dominant in total CBD (12.69 w/w)

with total THC (0.57% w/w), total CBC (0.72% w/w) and total CBG (0.17% w/w) (Table 1).

TABLE 1

Terpene (left column) and Cannabinoid (right column) profiles of 'Pure Red 3' mature flowers				
	Terpene	'Pure Red 3' [% w/w]	Cannabinoid	'Pure Red 3' [% w/w]
10	caryophyllene oxide	0.009	CBD	0.35
	beta-pinene	0.014	CBDA	14.07
15	D-limonene	0.015	Total CBD	12.69
	linalool	0.026	CBG	0.05
20	fenchol_bornylacetate	0.03	CBGA	0.14
	alpha-eudesmol	0.03	Total CBG	0.17
25	beta-eudesmol	0.039	d9-THC	0.04
	alpha-pinene	0.045	d8-THC	0
30	alpha-humulene	0.046	THCA	0.6
	All-E-Beta-farnesene	0.051	Total THC	0.57
35	selina-3,7(11)-diene	0.078	CBC	0.03
	beta-ocimene 2	0.079	CBCA	0.78
40	guaiol	0.086	Total CBC	0.72
	bisabolol	0.133	CBN	0
45	beta-caryophyllene	0.161	CBDV	0
	beta-myrcene	0.209	CBDVA	0.02
Total terpene content (% w/w)		1.049	Total CBDV	0.02

The genotype of 'Pure Red 3' was characterized using genotyping-by-sequencing (GBS). Short-read sequencing data produced by this method were aligned to the publicly available assembled genome of cs10 (Assembly: GCF_900626175.1) to identify single nucleotide polymorphisms (SNP) and short haplotypes (HAP, a combination of linked SNPs) in 'Pure Red 3' (Table 2 and FIG. 11). Together these polymorphisms provide a fingerprint which can be used to differentiate 'Pure Red 3' from all other *Cannabis* varieties known to the inventors.

Table 2 shows a list of single nucleotide polymorphisms (SNPs) and haplotypes (HAPs) contained within the genome of 'Pure Red 3' compared to the publicly available reference genome of cs10 (Assembly: GCF_900626175.1). Each record shows the reference chromosome of cs10, the nucleotide position on the cs10 reference sequence, the nucleotide sequence at this position, the nucleotide sequence displayed in 'Pure Red 3', and whether the state of the polymorphism is homozygous or heterozygous in 'Pure Red 3'. Heterozygous loci contain one allele sequence identical to the reference nucleotide sequence and one allele of the 'Pure Red 3' sequence.

THE CLONING PROCESS FOR VEGETATIVE OR ASEXUAL REPRODUCTION

Asexual or vegetative propagation methods (also known as cloning) are well-known to those skilled in the art. 'Pure Red 3' is cloned according to the following method: Coco peat plugs are soaked in pH-adjusted water and kept warm. Cuttings measuring 10-12 cm are taken 3 nodes from the branch distal meristem and trimmed of lower leaves. The cuttings are dipped in water and a commercial rooting agent and inserted into the warmed plugs. Trays are kept in continuous light conditions and high humidity for 7 to 15 days until rooted. Rooted plants may be transferred directly into the field for outdoor growth or used for greenhouse growth.

It was observed that all the desired characteristics of each clone are transferred by vegetative reproduction in a consistent and uniform fashion. The characteristics of 'Pure Red 3' are stable and the variety remains true-to-type through multiple generations of vegetative reproduction.

GROWTH OF PLANTS IN INDOOR ENVIRONMENTS

Rooted clones are transferred to two-gallon pots containing growth medium consisting of a mixture of soil, peat and perlite in a ratio of 3:3:1. Plants are grown in an indoor growth hall under completely supplied artificial high-pressure sodium (HPS) lighting (E-Papillon, 1000W, 400V). The air in the room was circulated with a fan and the humidity was kept constant at 45-55%. Commercial fertilizer is applied at a dose of 70-80% of the amount recommended by the manufacturer (Plagron, NL). The plants are grown for 10 days with a light intensity between 700-800 $\mu\text{mol m}^{-2} \text{s}^{-1}$, 18 h light/6 h dark day-night photoperiod with a 24-25°C. day/18°C. night temperature. The photoperiod is then changed to a 12 h light /12 h dark day-night cycle and the light intensity increased by 100 $\mu\text{mol m}^{-2} \text{s}^{-1}$ per day for 7 days, at 25°C. day/23°C. night temperatures. During the following 60 days the light intensity is adjusted to 1400-1500 $\mu\text{mol m}^{-2} \text{s}^{-1}$ with a 12 h light/12 h dark day-night photoperiod and a 24-25°C. day/18°C. night temperature. After a total of 84-91 days of growth after cloning, the flowers are harvested.

GROWTH OF PLANTS OUTDOORS

Field growth of 'Pure Red 3' was performed in Niederwil, CH (47°22'49.9"N 8°18'12.6"E) during the summer of 2022. The weather during the year of 2022 is presented in FIG. 11. Rooted clones were planted in the field on the 21st of July 2022 with a row distance of 1.5 m and planting distance of 750 cm. Plants were planted in foil strips for weed control and drip irrigation was installed under the foils. Initial fertilizer was applied with a slurry and irrigation supplied as needed. Mature flowers were then collected during the first two weeks of October 2022.

BRIEF DESCRIPTION OF THE DRAWINGS

FIG. 1: Mature plants of the 'Pure Red 3' variety grown in greenhouse conditions. Photos taken from two different angles clearly illustrate the architecture of the plant. Ruler for scale with cm markings.

FIG. 2: Abaxial leaf surfaces sampled from the (A) lower, (B) middle, and (C) upper third of the mature 'Pure Red 3'

plant. Ruler for scale with cm markings and RHS colors swatches alongside to indicate the color.

FIG. 3: Adaxial leaf surfaces sampled from the (A) lower, (B) middle, and (C) upper third of the mature 'Pure Red 3' plant. Ruler for scale with cm markings and RHS colors swatches alongside to indicate the color.

FIG. 4: Detailed photos of leaves from the lower third of the mature 'Pure Red 3' plants. (A) The adaxial leaf surface, (B) abaxial midrib, (C, D) adaxial petiole, (E) glandular bulbous trichomes on adaxial leaf surface.

FIG. 5: Detailed leaf images from the middle third of the mature plant. (A) Adaxial midrib, (B) Abaxial midrib, (C, D) adaxial petiole with uni-cellular non-glandular hairs and purple anthocyanin coloration, (E) glandular bulbous trichomes on adaxial leaf surface.

FIG. 6: Detailed leaf images from the upper third of the mature plant. (A, B) Adaxial leaf surface illustrating the presence of bulbous glandular trichomes, (C, D) abaxial leaf surface covered in uni-cellular non-glandular hair, (E, F) adaxial petiole showing significant purple anthocyanin coloration and uni-cellular non-glandular hairs.

FIG. 7: 'Pure Red 3' stems. (A, B) Stem samples from the lower, middle and upper third of the plant are placed alongside a ruler for scale with cm markings and RHS colors swatches alongside to indicate the color. (C, D, E) Detailed photos of the stem surface illustrating the smooth stem with a solid, pithy center (F).

FIG. 8: Mature flowers from 'Pure Red 3' plants grown in a greenhouse. (A, B) Untrimmed flowers and (C-F) hand trimmed flowers. Ruler for scale with cm markings and RHS colors swatches alongside to indicate the color.

FIG. 9: Detailed images of 'Pure Red 3' flowers. (A, B) Floral bracts with distinct purple anthocyanin coloration, (C) orange/grey stigmas protruding from the floral bracts, (D) capitate stalked trichomes on a reduced leaf that emerge from between the inflorescences.

FIG. 10: Annual temperature, rainfall, and wind data for (A) Zeinlingen and (B) Niederwil for 2022.

FIG. 11: A graphical representation of the single nucleotide polymorphisms (SNP) and haplotypes (HAPs) contained within the genome of 'Pure Red 3' when compared to the publicly available reference genome of cs10 (Assembly: GCF_900626175.1).

DESCRIPTION OF THE NEW VARIETY

The 'Pure Red 3' plants described herein were grown both in nurseries, climate-controlled growth facilities in Zeinlingen, CH, 4314 (47°32'53.5"N 7°51'53.2"E), and in the field in Niederwil, CH (47°22'49.9"N 8°18'12.6"E). Observed phenotypes may vary in different environmental conditions.

Plants used for the botanical description are annual, herbaceous, upright, tap-rooted plants. They are *Cannabis* hybrid species and the particular variety described herein is designated 'Pure Red 3'.

Throughout this specification, color names signify that the name of that color, as used in common speech is aptly descriptive. Color number descriptions were obtained using the 6th revised edition of the RHS (Royal Horticultural Society) color chart.

'Pure Red 3' is a cross between multiple plants of the pollen donor variety 'Amnesia Haze' (unpatented) and several plants of the pollen acceptor variety 'Strawberry Haze' (unpatented). The initial cross was made in 2018 in Zeinlingen, Switzerland. The resulting F1 seeds were grown,

cloned, and the clones used for crossing i.e. selfed. The F2 seeds were grown, and from this population 'Pure Red 3' was selected. The selection criteria were based on the following characteristics: Pungent strawberry smell in the mature flower, flower density, and a highly branched plant structure. The variety was first vegetatively reproduced on the 12th of April 2019 and the resultant plants screened for strong strawberry aroma and selected based on production relevant phenotypes. The progeny with the most stable desirable chemotype was assigned the name, 'Pure Red 3'. 'Pure Red 3' continues to be vegetatively reproduced by cloning in Zeiningen, Switzerland.

Compared to 'Strawberry Haze', 'Pure Red 3' has a much lower total CBD content (12.69% vs 21%), and higher THC content (0.57% vs <0.2%). 'Pure Red 3' also has a distinct and notably stronger strawberry aroma. 'Pure Red 3' has CBD concentrations comparable to those in 'Amnesia Haze'. The strong strawberry aroma of 'Pure Red 3' does not resemble the lemon and floral notes found in 'Amnesia Haze'. 'Pure Red 3' notably has distinct purple anthocyanin coloration in the apical regions that are not evident in the parent varieties.

The new variety 'Pure Red 3' is a *Cannabis* strain that is distinct from the commercial variety 'Bubblegura' (unpatented). The new variety 'Pure Red 3' has a lower total CBD content (12.69% vs. 15%) and a similar THC content (0.57% vs. 0.6%) as 'Bubblegum'. However, the new variety 'Pure Red 3' has a strong strawberry aroma, while 'Bubblegum' has a sweet and mild-citrus aroma. Additionally, the new variety 'Pure Red 3' displays a distinct purple anthocyanin coloration in the apical regions, while 'Bubblegum' does not.

The new variety 'Pure Red 3' is also distinct from the variety 'Cannatonic' (unpatented). The new variety 'Pure Red 3' has a lower CBD content (12.69% vs. 17.5%) than 'Cannatonic', but a similar THC content (0.57% vs. 0.6%). Additionally, the new variety 'Pure Red 3' has a strong strawberry aroma compared to the woody and clove aromas of 'Cannatonic'. Lastly, unlike the new variety 'Pure Red 3', 'Cannatonic' does not display a distinct purple anthocyanin coloration in the apical regions.

Below is a detailed description of the new variety 'Pure Red 3'. Unless otherwise stated measurements were taken from mature plants grown in a greenhouse. The 'Pure Red 3' cultivar is a mixed hybrid of the *Cannabis* sp. It is naturally obtained and not the result of any genetic modification techniques.

Plant:

Plant life form and growth habit.—An annual herbaceous plant described as broad, upright, tap-rooted.

Plant propagation.—Asexually propagated by cutting and cloning methods.

Propagation ease.—'Pure Red 3' is easy to propagate.

Height.—Approximately 40 cm-70 cm.

Width.—Approximately 20 cm to 40 cm.

Plant vigor.—Medium — 'Pure Red 3' bears mature flowers with a high flower:total biomass without the requirement for excessive growth.

Time to harvest.—From time of planting the plant will take approximately 9.7 weeks to be harvest-ready.

Resistance to pathogens.—Moderate to high susceptibility to *Botrytis cinerea* with the tipping point after maturity and at high humidity. 'Pure Red 3' has low to moderate susceptibility to powdery mildew and leaf spot in outdoor conditions. In greenhouse envi-

ronments it is highly susceptible to powdery mildew. 'Pure Red 3' shows high resistance to insect pests.

Genetic modification.—It is naturally obtained and not the result of any genetic modification techniques.

Conditions of flowering.—'Pure Red 3' flowers once the daylight period is reduced to 14.3 hours daylight.

Hardiness.—'Pure Red 3' easily tolerates temperatures up to 32° C.

Breaking action.—'Pure Red 3' is short and sturdy and highly resistant to breaking during heavy winds. This plant is not prone to lodging.

Rooting behavior.—When propagated according to Puregene's standard operating procedures, it roots vigorously.

Leaf:

Arrangement.—Alternating.

Shape.—Palmately compound.

Structure.—Leaflet blades are very elongated, elliptical, lanceolate with acute to acuminate tips and bases.

Margins.—Serrated with teeth forward pointing.

Hairs.—Extremely fine sericeous hairs pointing toward the leaf tips.

Mature leaf measurements.—Leaf length with petiole: Approximately 9-15 cm. Petiole length: Approximately 2.5-4 cm. Stipule length and shape: Approximately 0.2 cm to 0.8 cm linear with acute tip. Leaflet number: About 5. Middle leaflet length:width: Approximately 9:1.5. Teeth on middle leaflet: Approximately 18 to 28. Middle largest leaflet length: Approximately 9 cm. Width of central leaflets: Approximately 1.5 cm.

Leaflet apex shape.—Acuminate acute.

Adaxial leaf trichomes.—Capitate stalked, capitate sessile and cystolithic trichomes.

Abaxial leaf trichomes.—Capitate stalked, capitate sessile and cystolithic trichomes.

Abaxial petiole color range.—About Medium Yellow-Green 144B with gradual anthocyanin coloration of Medium Red-Purple 58A during flowering.

Adaxial petiole color range.—About Medium Yellow-Green 144B with gradual anthocyanin coloration of Medium Red-Purple 58A and 58B during flowering.

Stipule color range.—About Dark Green 137A and 137B.

Leaflet color of the adaxial surface.—About Dark Green 137A and 137B in the lower leaves to Dark Green 137B in the middle leaves and becoming slightly mottled with purple Dark Purple 79A toward the apical growth point.

Leaflet color of the abaxial surface.—Ranging from Medium Yellow-Green 144A in the lower leaves to Medium Yellow-Green 144B in the middle of the plant with distal leaf tips transitioning to Medium Red-Purple 58A. Leaves proximal to the flowers are yellow green Light Yellow-Green 144C mottled with red purple coloration of Dark Red-Purple 59A.

Leaflet glossiness.—Average, becoming more matt at the apical ends as flowers mature.

Midrib shape.—Prominent and continuous throughout each leaflet.

Midrib color.—The midrib on the adaxial leaf surface appears around Dark Green 137A. On the abaxial side it appears about Light Yellow-Green 145D.
